CASEMENT WINDOW

Filed Dec. 1, 1930

INVENTOR

G.R. SHAW

by *Johnnie Shaw*

UNITED STATES PATENT OFFICE

GEORGE REGINALD SHAW, OF LONDON, ENGLAND

CASEMENT WINDOW

Application filed December 1, 1930, Serial No. 499,339, and in Great Britain December 9, 1929.

This invention relates to improvements in casement windows and has for its object the production of a window which is proof against forcible entry even when open, except of course by smashing the glass, prevents direct draught when open, prevents entry of rain, snow or sleet, and which can be cleaned on the outside from the inside of the room.

According to this invention the window is made in two vertical halves which are hinged to the opposite stiles or other fixed part of the window frame, and in such a manner that the two halves can rotate on their hinges so as to be angularly disposed to one another when the window is shut, the apex of the angle pointing inwards thus forming a bay window with the bay towards the inside. When open for the purpose of ventilation the central stiles of the two halves of the window abut against each other.

Each half of the window is held in desired position by a casement stay, and each half can be opened right out independently of the other when required.

The fixed mullion, against which each half of the window abuts when shut, tapers smaller from the inside to the outside and is rebated at the proper angle to accommodate the window central stiles.

The rear of the window frame stile to which each half of the window is hinged, is cut at an angle so that when secured in position, the rebates for accommodating the stiles are inclined, instead of parallel to the thickness of the wall.

In order to permit of this arrangement the window frame is fixed in position near the outside of the wall, whilst the mullion is fixed near the inside of the wall and centrally of the aperture.

One of the window halves has a stop plate, fixed to the outside and projecting across the meeting line of the vertical central stiles. When both halves are opened together, the other half of the window will abut against this stop, when the two halves are in line, and the halves can then be held

in this position by securing the casement stays.

The invention is illustrated in the accompanying drawing showing a plan section through a window and adjoining wall. 55

In this drawing 1 indicates the wall of the building in which the window is mounted and 2 the sill. The window frame stiles 3, 3 have their rear faces cut at an angle and are secured to the wall 1 in any usual manner. The front faces of the window frames stiles 3, 3 are rebated at 4 to accommodate the outside vertical stiles 5, 5 of the window halves 6, 6. As will be seen from the drawing, when the stiles 3, 3 are fixed 60 in position the rebates 4, 4 are inclined to the thickness of the wall. Each half 6, 6 of the window is hinged to a window frame stile 3, 3 and owing to the inclination of the rebates 4, 4, the halves of the window, when 65 shut, will incline inwards, the stiles 7, 7 abutting against the inclined rebates of the central mullion 8. To permit of the proper fitting of the stiles 7, 7 against the mullion 8, it is tapered smaller from the inside to 70 the outside. 75

When the window halves 6, 6 are opened out, the stiles 7, 7 thereof will abut against each other when the two halves are in a straight line. This position is shown in 80 dotted lines in the drawing. To hold the window in this position one of the stiles 7, 7 is provided with an external stop plate 9 secured to or made in one with the stile and extending across the meeting line of the two 85 stiles 7, 7. The window can then be locked in this position by securing the casement stays 10, 10 in the usual manner.

I claim:—

1. A casement window comprising two 90 vertical halves hinged near the outer side of the wall to opposite stiles of a window frame, a mullion fixed centrally of the window frame and near the inner side of the wall and means for opening and closing 95 said window halves.

2. A casement window comprising two vertical halves hinged near the outer side of the wall to opposite stiles of a window frame, a mullion fixed centrally of the win- 100

dow frame and near the inner side of the wall, said mullion tapering smaller from inside to outside, inclined rebates on said mullion to accommodate the inner stiles of the window halves, and means to open and close said window halves.

5 3. A casement window comprising two vertical halves hinged near the outer side of the wall to opposite stiles of a window frame, inclined rebates on said window frame stiles, a mullion fixed centrally of the window frame and near the inner side of the wall, said mullion tapering smaller from inside to outside, inclined rebates on said mullion to accommodate the inner stiles of the window halves, and means to open and close said window halves.

10 4. A casement window comprising two vertical halves hinged near the outer side of the wall to opposite stiles of a window frame, inclined rear faces on said window frame stiles, rebates on said window frame stiles, a mullion fixed centrally of the window frame and near the inner side of the wall, said mullion tapering smaller from inside to outside, inclined rebates on said mullion to accommodate the inner stiles of the window halves, and means to open and close said window halves.

15 5. A casement window comprising two vertical halves hinged near the outer side of the wall to opposite stiles of a window frame, an external stop plate on one of said vertical halves, inclined rear faces on said window frame stiles, rebates on said window frame stiles, a mullion fixed centrally of the window frame and near the inner side of the wall, said mullion tapering smaller from inside to outside, inclined rebates on said mullion to accommodate the inner stiles of the window halves, and means to open and close said window halves.

20 In testimony whereof I have hereunto set my hand this 18th day of November 1930.

GEORGE REGINALD SHAW.
